PULL TAB FOR A TEAR STRIP OPENER

John S. Bozek, Chicago, Ill., assignor to Continental Can Company, Inc., New York, N.Y., a corporation of New York

Filed Apr. 10, 1964, Ser. No. 79,442

Term of patent 14 years

(Cl. D58—26)

FIGURE 1 is a top perspective view of a pull tab for a tear strip opener showing my new design, the portions shown in broken lines being for illustrative purposes only;

FIGURE 2 is an enlarged top perspective view thereof;

FIGURE 3 is a bottom perspective view thereof on the same scale as FIGURE 2;

FIGURE 4 is a top plan view thereof on a further enlarged scale;

FIGURE 5 is an end elevational view thereof from the left of FIGURE 4;

FIGURE 6 is a side elevational view of FIGURE 4; and

FIGURE 7 is an end elevational view taken from the right of FIGURE 4.

I claim:

The ornamental design for a pull tab for a tear strip opener, as shown and described.
